UNITED STATES PATENT OFFICE.

JENS WEIMANN, OF ODENSE, DENMARK.

ROBE AND THE LIKE.

1,403,661.

Specification of Letters Patent. Patented Jan. 17, 1922.

Application filed January 4, 1921. Serial No. 435,045.

To all whom it may concern:

Be it known that I, JENS WEIMANN, a subject of Christian X, King of Denmark, residing at Odense, Denmark, have invented 5 certain new and useful Improvements in Robes and the like, of which the following is a specification.

This invention relates to apparel and particularly to such outdoor articles as lap 10 robes or other protective articles.

In such an article as a lap robe, to which reference is made by way of illustration, it is of the greatest importance that warmth be combined with lightness and flexibility, 15 that the effects of inclement weather be provided for, that the article have a very considerable strength to withstand the rough usage which seems inevitable and that more specifically the article be of a form providing 20 for comfort and convenience.

As illustrative of my invention and as characteristic of one of its preferred forms, I have illustrated herein a lap robe combining the features set forth as desirable. 25 Throughout the specification and drawings like reference characters are employed to indicate corresponding parts, and in the drawings:—

Fig. I is a general view of an automobile 30 robe.

Fig. II is an enlarged face view of one of the pockets.

Fig. III is a section through the pocket of Fig. II, and

Fig. IV is a section through the robe at an edge thereof.

In general form the robe 1 shown is of 40 general dimensions but is provided with a pair of patch pockets 2 located a sufficient distance apart to provide for the comfortable envelopment of a pair of passengers so that a pocket will naturally lie substantially in the lap of each passenger. The pockets 2 are substantially independent of 45 the robe 1 being attached only at top and bottom leaving the sides unattached. Within the lateral openings thus formed beneath the pocket I preferably gather in a member 3 having a central opening for the admission 50 of the hand. This opening is preferably provided with an elastic and the member 3 is suitably gathered to give freedom.

The space between the pockets 2 and the face of the robe 1 may be further interlined 55 if desired and thus forms with or without the lining a muff or a hand warmer which

at the same time assures the positioning of the robe snugly against the body of the passengers so that it can not slip down or become misplaced. The pair of pockets also 60 make an easier means of apportioning the robe justly between two passengers and of preventing the robe from becoming untucked on one side and overtucked on the other.

The structure of the main body of the robe 1 is of great importance. It is highly desirable in a robe of this sort that it not only be wind proof but rain proof. It is of course a well known fact that the skins of 70 animals make one of the most satisfactory protections against wind and cold known to man. Not all skins, however, are sufficiently flexible to be comfortably used as garments. Furthermore, skins capable of flexible cur- 75 ing are usually affected by water when so cured.

One of the most characteristic skins available for this purpose is that of the sheep. Sheep skin as is well known is capable of 80 being dressed with a great degree of flexibility and softness so that it conforms readily to the body. It is very warm, keeping in the heat and keeping out the cold and at the same time being sufficiently light 85 so that it will not drag or weigh down on the users. Such skins as sheep skins so prepared take on moisture very readily and when wet present all kinds of difficulties. In the first place, the very wetness of a skin 90 renders it useless for warmth or comfort and at the same time the skin when wet is very easily distorted, stretched and sagged. This stretching and sagging is a fault that is apparent even with the dry skin but is 95 very much aggravated and increased with any moisture which has been absorbed.

In order to overcome this difficulty and at the same time gain the advantages of this class of hide I provide a soft tan sheep skin 100 inner lining 10 carried throughout the body of the robe. On each side of this sheep skin lining 10 I provide a surfacing layer 11 preferably of waterproof fabric. These external surfaces of fabric not only protect 105 the sheep skin against moisture but they take up wear and increase the attractiveness and appearance of the robe.

I furthermore strengthen and protect my robe by an inextensible binding of leather 12 110 of a character which is not itself affected by moisture, and which is stitched to the edges

of the fabric 11 and interlining 10 and a robe so framed in its binding is found to possess great strength in all directions and great freedom from any tendency to bunch or sag or stretch or be otherwise distorted.

I have referred to the freedom between the surface members and the binding. This, however, is not to be misunderstood as complete and absolute non-attachment in all cases. For example, in large robes, I sometimes run rows of stitching across the robe, sub-dividing it somewhat. The members are, however, substantially free throughout and such stitching or sub-division of the robe 15 by stitching in certain cases might be desirable.

My robe may be of a variety of materials of the character specified and may be variously designed and trimmed, all without departing from the spirit of my invention if 20 within the limits of the appended claims.

What I therefore claim and desire to secure by Letters Patent is:—

1. In a robe of the class described, an interlining of soft dressed leather, a water proof fabric surfacing on each side thereof and united thereto at the edges, and an inextensible binding about the edges of the robe and receiving and retaining the leather 30 and fabric of the robe body.

2. In a robe of the class described, an interlining of soft dressed leather, a water proof fabric surfacing on each side thereof and united thereto at the edges.

3. In a body covering, a body portion, a pocket structure comprising an inside piece secured at its top and bottom edges to the outer face of the body portion but free from the body portion at its lateral edges and defining therewith an open-sided pocket within which the hands may be entered, an outside piece secured at its bottom and lateral edges to the inside piece and defining therewith an open top pocket for the reception of various 45 objects, and separable fastening means for closing the open top of said last named pocket.

4. In a robe of the class described, a body portion, a patch pocket disposed thereon so as to lie substantially in the lap portion of the robe, said pocket being attached at top and bottom, but unattached on the two sides and forming a hand receiving portion between the pocket and the robe, and a gathered closure within said lateral opening and having a resiliently bordered hand hole therein.

5. In a body covering, a body portion, a

pocket structure comprising an inside piece secured at its top and bottom edges to the outer face of the body portion and defining therewith an open-sided pocket within which the hands may be entered, an outside piece secured at its bottom and lateral edges to the inside piece and defining therewith an open top pocket for the reception of various objects, and a flap at the upper edge of said inside piece adapted to be folded over the outside piece and detachably engaged therewith to close the open top of said last named 70 pocket.

6. In a robe of the class described, a body portion, a pair of patch pockets spaced apart thereon so as to lie substantially in the two lap portions of the robe, each of said pockets being attached at top and bottom but unattached on the two sides and forming a hand receiving portion between the pocket and the robe, and a gathered closure within said lateral opening and having a resiliently 75 bordered hand hole therein.

7. In a robe of the class described, an interlining of soft dressed absorptive leather, a water proof fabric surfacing on each side thereof and united thereto at the edges, and a water proof inextensible binding about the edges of the robe and receiving and retaining the leather and fabric of the robe body, and a patch pocket attached at top and bottom to the fabric surface of the robe but unattached on the two sides and forming a hand receiving portion between the pocket and the robe.

8. In a body covering, a body portion, a pocket structure comprising an inside piece secured at its top and bottom edges to the outer face of the body portion but free from the body portion at its lateral edges and defining therewith an open sided pocket within which the hands may be entered, an outside piece secured at its bottom and lateral edges to the inside piece and defining therewith an open top pocket for the reception of various objects, said outside piece comprising a layer of soft dressed leather and a waterproof fabric applied to the outer face of said leather layer, and separable fastening means for closing the open top of said last named pocket.

In testimony whereof I affix my signature 110 in presence of two witnesses.

JENS WEIMANN.
